UNITED STATES PATENT OFFICE

GUY L. BONHAM, OF WEST HARTFORD, CONNECTICUT

GAME APPARATUS

Application filed June 27, 1930. Serial No. 464,396.

This invention relates to a game apparatus and has for its object to provide a ball adapted to swing like a pendulum when propelled by the player, a series of pins or game pieces being set up where the ball will strike them on its return movement if properly directed.

A further object is to provide a resilient stop for the ball whereby its swinging movement in one direction is limited.

10 A still further object is to provide a stop which, if desired, can be utilized for imparting a supplemental impulse to the ball at the beginning of its return movement.

A still further object is to provide an apparatus which includes as a complete unit, a suitable inclosure for the game pieces, a supporting frame for the ball and its resilient stop, and a means for holding the ball in inactive position where it can be reached 20 readily by a player.

With the foregoing and other objects in view which will appear as the description proceeds, the invention resides in the combination and arrangement of parts and in the details 25 of construction hereinafter described and claimed, it being understood that changes in the precise embodiment of the invention herein disclosed may be made within the scope of what is claimed without departing from the 30 spirit of the invention.

In the accompanying drawings the preferred form of the invention has been shown.

In said drawings

Figure 1 is a plan view of the game apparatus.

Figure 2 is a front elevation.

Figure 3 is a view partly in side elevation and partly in section.

Figure 4 is an enlarged section through the 40 ball rest.

Figure 5 is a plan view of a portion of the resilient stop.

Referring to the figures by characters of reference, 1, 2, and 3 designate front posts 45 connected by rails 4 to which is connected a coarse fabric 5, preferably of metal which constitutes a guard. One of these posts, 3, is extended upwardly above the upper rail 4 and is provided with a cup 6 lined with felt 50 7 or other suitable soft material and adapted

to hold the ball B of the game apparatus when not in use. Post 2 does not extend above the rail 5, but the post 1 extends upwardly like post 3 and to the upper end portions of the posts 1 and 3 are connected side rails 8. Additional side rails 9 and 10 are connected to the posts 1 and 3 and extend backwardly therefrom, these rails 9 and 10 being attached to panels 11 of metal fabric or the like constituting guards.

At their rear ends the rails 8, 9, and 10 are connected to posts 12 which, in turn, are connected by back rails 13, 14, and 15. Rails 14 and 15 are connected by a rear guard panel 16. An intermediate post 17 is connected to 60 the middle portions of the rails 13, 14, and 15, and terminates at its upper end at the level of the top rail 13.

Intermediate side posts 18 are connected to the rails 8, 9, and 10, and converge upwardly from the rails 8 to a short bar 19, which, in turn, is connected by braces 20 to the upper ends of the posts 12. A cross rail 21 can connect the upper ends of posts 12 and arranged back of this cross rail is 70 an arcuate frame member 22 inclined downwardly and rearwardly from the rail 21 and supported at its center by a brace 23 which is extended upwardly and rearwardly from the upper ends of the metal rear post 17.

Arranged within the space defined by the cross rail 21 and the arcuate member 22 is a back stop 24 formed of heavy canvas or any other suitable fabric, the edges of which are connected to the rail 21 and the frame member 22 by springs 25 which are constantly under tension. Thus the back stop 24 is held normally taut.

A base in the form of a triangular board 26 or the like is adapted to be placed on the 90 supporting surface beneath the converging portions of the posts 18 and serves to support the game pieces 27 which can be ten pins.

The ball B is adapted to be connected to the bar 19 by a length of flexible material 95 such as a strong cord 28.

In practice the ball normally rests in the cup 6 as shown. At this time the connection 28 hangs slack. The game pieces 27 are placed on the base 26 after said base has been 100

positioned with its center at one side of a vertical line extending through the center of bar 19 where the connection 28 is attached.

The head pin is arranged toward the back of the apparatus. The player removes the ball B from the cup 6 and releases it so that it will swing under the posts 18 and toward the back stop 24 without coming into contact with the game pieces. On its return movement the ball, if properly guided, will strike certain of the pins. The back stop 24 limits the swinging movement of the ball, and if the ball is propelled thereagainst forcibly, certain of the springs 25 will elongate and thereafter promptly contract so that an impulse will be imparted to the ball at the beginning of its return stroke.

This game apparatus can be set up out of doors or in large rooms, and will be found to be an entertaining substitute for the ordinary game of ten pins.

If desired, and as shown in Figure 2, the collapsible desk 29 of any preferred construction can be removably mounted on the side rails 8 and 9 where scores can be kept.

What is claimed is:

Game apparatus including game pieces, a structure extending thereover, a ball suspended from said structure and adapted to be swung relative thereto so as to strike the game pieces on the return movement of the ball toward the player, and a resilient back stop in the path of the ball, and inclined downwardly away from the player, said back stop including a flexible strip adapted to be engaged by the ball when reaching one limit of its movement, and yielding means for holding the strip normally taut, and expediting the return of the ball in the direction of the game pieces.

In testimony that I claim the foregoing as my own, I have hereto affixed my signature.

GUY L. BONHAM.
